UNITED STATES PATENT OFFICE.

GEORGE M. BOLL, OF MOUNT HOPE, KANSAS.

GRAIN-BIN.

933,617.

Specification of Letters Patent. Patented Sept. 7, 1909.

Application filed September 22, 1908. Serial No. 454,197.

To all whom it may concern:

Be it known that I, GEORGE M. BOLL, a citizen of the United States, residing at Mount Hope, in the county of Sedgwick and State of Kansas, have invented certain new and useful Improvements in Grain-Bins; and I do hereby declare the following to be a full, clear, and exact description of the invention, such as will enable others skilled in the art in which it appertains to make and use the same.

My invention relates to granaries or bins for the storage of grain and particularly to the construction of the door through which the grain is removed.

It has for its object to provide additional protection against theft and to preserve the grain in the vicinity of the door against moisture and fire.

Another object is to strengthen the wall of the bin to offset the weakening caused by cutting away a part thereof to form the doorway.

The invention also contemplates the construction of the door in such a manner and of such size as to permit of the passage of persons therethrough whereby the bin may be used for other purposes when grain is not stored therein.

The invention consists of a double door, the outer one being constructed of heavy material and hinged to swing outwardly while the inner door is composed of sliding sections which are separably removable. Additionally truss bars are placed across the doorway between the inner and outer doors.

The invention also consists in the features of construction and combinations of devices herein-after described and specified in the claims.

In the accompanying drawing illustrating the preferred embodiment of my invention: Figure 1 is an elevation of a circular metal bin provided with a door constructed in accordance with my invention. Fig. 2 is a broken elevation showing the door on an enlarged scale, the outer door being open. Fig. 3 is a broken elevation of a portion of the interior of the bin showing the slides holding the sections of the inner door. Fig. 4 is a vertical sectional view on the line $x-x$ of Fig. 1, and Fig. 5 is a horizontal sectional view on the line $y-y$ of Fig. 1.

Referring more particularly to the drawing, the granary or bin 1 is constructed of sheet metal in any suitable manner. A door

way or opening 2 is cut in the walls of the bin of sufficient height and width to permit persons to pass therethrough. Around the outer edge of said doorway there is secured a projecting frame 3 composed of angle irons riveted to the walls. Portions of the top and bottom angle irons are extended to one side to form hinge-lugs 4. The outer door 5 is constructed of a sheet metal plate 6 around the edges of which are riveted inwardly extending angle irons 7. The top and bottom angle irons on the door are extended on one side to form other hinge-lugs 8 which are secured to the lugs 4 of the door frame by pivot pins 9. The angle irons of the door are adapted to fit outside of the angle irons of the door frame. The angle iron on the side of the door next to the hinge-lugs is cut away, as at 10, adjacent to said lugs to fit over the hinge-lugs of the door frame when the door is closed. The door should fit the frame closely so as to be as near air tight as possible and prevent the entrance of moisture or fire. Any suitable locking device may be employed for securing the door.

The sliding sections 11 composing the inner door are arranged in vertical channel-pieces 12 which are preferably riveted to the sides of the inner door frame comprising angle irons 13 which are in turn riveted to the inner edge of the doorway. Said angle irons are secured by the same rivets which fasten the angle irons composing the outer door frame. A portion of each channel-piece at the top of the doorway is cut away, as at 14, to permit the upper section to be removed inwardly. After the upper section is removed each of the other sections may be raised and taken out in turn through said cut out portions. The upper section is retained in place by having its upper edge engage a groove in a channel or U-shaped iron 15 which is constructed similarly to the lower parts of the channel-pieces and is fastened to the top angle iron of the inner door frame. The lower edge of the upper section is provided with a pivoted latch 16 adapted to be turned down outside of the next lower section. When it is desired to remove said upper section, the latch is released whereupon the lower edge of said section may be pushed inward and its upper edge afterward removed from the groove in the top channel iron 15.

The wall of the bin is strengthened where

the doorway is cut by adjustable truss rods 17 which may be placed at the desired distance apart. Each of said truss rods comprises two parts 18 which are hinged to the 5 opposite edges of the doorway and are connected by a turnbuckle 19. Said truss rods are arranged between the inner and outer doors, the hinged parts being connected to loops or staples 20 which are passed through 10 and secured to the projecting portions of the angle irons forming the inner and outer door frame. When the bin is partially or entirely emptied, the truss rods may be disconnected at the turnbuckle, allowing the 15 opposite parts thereof to fall down and hang along the edges of the doorway as illustrated in dotted lines in Fig. 2.

I claim:

The combination, with the wall of a 23 grain bin having a doorway therein, of an outer door frame and an inner door frame projecting respectively from the outer and

inner faces of said wall, a flanged outer door adapted to close around the outer frame, said inner door frame being provided with 25 grooves at its sides, and a plurality of removable door sections arranged in said grooves.

2. The combination, with the wall of a grain bin having a doorway therein, of an 30 outer door frame and an inner door frame both comprising angle irons secured by the same rivets to the outer and inner edges of said doorway, an outer door adapted to close upon the outer frame, channel-pieces secured 35 to the lateral edges of the inner frame, and a plurality of door-sections arranged in said channel-pieces.

In testimony whereof, I affix my signature, in presence of two witnesses.

GEORGE M. BOLL.
